UNITED STATES PATENT OFFICE.

MAXIMILIAN JOSEPH SALM, OF HANAU, GERMANY, ASSIGNOR OF ONE-HALF
TO LUDWIG LIMBERT, OF SAME PLACE.

ENGRAVING-MACHINE.

SPECIFICATION forming part of Letters Patent No. 274,391, dated March 20, 1883.

Application filed January 11, 1883. (No model.)

To all whom it may concern:

Be it known that I, MAXIMILIAN JOSEPH SALM, a person resident at Hanau, in the Empire of Germany, have invented new and useful Improvements in Engraving-Machines, of which the following is a specification, reference being had to the accompanying drawings.

This invention relates to machines designed to produce artistic objects in hard and soft stone, glass, metal, ivory, wood, or other suitable material, without any artistic ability, similar to a given model, and either of the same size, smaller, or larger, as desired. Moreover, models can be reproduced by the said machine in counterparts, and existing reliefs can be transposed or transferred with sunk work, and vice versa.

Figure 1 in the accompanying drawings is a plan of a machine embodying my invention. Fig. 2 is a central vertical section of the same. Fig. 3 is an elevation, partly sectional, on a larger scale than Figs. 1 and 2, of some of the details of the machine.

In carrying the said invention into practice I provide a vertical spindle, W, which passes through a bearing in the table or plate T. This spindle is also guided by corresponding bearings in the bridge-piece E and the cross-piece H, so that it can be easily rotated upon its axis, and can also be moved upward or downward, being always kept vertical by the said bearings. The pantograph P is fixed at its central portion on this spindle, above the said table or plate. On the said table or plate are raised parts N, which are provided with longitudinal stops having at the top dovetailed grooves, which form guides for the sliding blocks K. These sliding blocks K are provided with screw-threads in their lower part, 40 through which pass the screws D. The latter are connected at the three corners C of the table by miter-wheels, one of the screws being continued and projecting beyond the front edge of the table, and carrying a hand-wheel, R, by which the screws can be turned, and by this means the sliding blocks can be shifted simultaneously through equal distances.

The material B, from which the copies have to be made, is fixed in any well-known manner 50 to three of the said sliding blocks, while the

model B', Fig. 1, which has to be copied or reproduced, is fixed to the fourth sliding block. The three corners of the pantograph which lie above the material to be operated upon are provided with drills. The latter are connected to small pulleys, which, by means of a cord or band, are connected to the pulley S in such a manner that when the latter is set in motion the three drills commence to rotate. At the fourth corner of the pantograph the guide-pin 60 r' is fixed.

The operation of this machine is as follows—that is to say: After the material B to be operated upon has been fixed upon the said three sliding blocks K and the model B' upon the fourth block, the drills are set in motion by means of the said pulleys S. By the weight of the central spindle, W, and the pantograph P the drills are pressed upon and caused to enter the material below them. As soon, however, 70 as the said guide-pin touches the model below it, the spindle and the pantograph fixed to it are prevented from being pressed farther down. By this time the said drills have at the parts operated upon removed so much of 75 the material fixed upon the said three sliding blocks K that the thickness of the said parts is equal to that of the model at that part where the guide-pin touches it. The spindle of the pantograph is now raised, and by altering the 80 position of the pantograph the adjoining parts of the material are moved in a similar manner. The movement of the pantograph, which is regulated by the guide-pin, must take place in only one direction—that is to say, if the 85 grinding or drilling is commenced at the foot of the model representing the figure B', Fig. 1, the guide-pin is to be moved in a straight line toward the head of the figure. The drills fixed at the other three corners of the pantograph are then also moving in straight lines. A straight groove is in this manner formed in the material at the places operated upon, the depth of which groove is in inverse proportion 90 to the height of that part of the model over 95 which the guide-pin is caused to move. As soon as such a groove is formed in the entire length of the model the sliding blocks are shifted by a partial rotation of the aforesaid hand-wheel R, so that the drills now operate 100

upon and remove the material on one side of the said groove, and thus widen the same. The guide-pin can then be moved in a direction exactly opposite to the previous one. By this 5 gradual and repeated to-and-fro movement of the guide-pin over the model, in connection with the shifting of the sliding blocks, the superfluous material is removed by the drills, and a figure is produced on each of the three sliding blocks which corresponds exactly with the model. When in working on very hard materials the pressure which is exerted on the point of operation by the weight of the spindle and the pantograph is not sufficiently great, 10 then it can easily be increased by shifting the ring G on the lower part of the central spindle, W, a little higher up, whereby the spiral spring F, between the said ring and the table T, is compressed, and by its elasticity increases the pressure 15 in the manner desired. If, on the contrary, the pressure resulting from the weight of the spindle and pantograph is too great, then the spiral spring F is removed from the lower end of the spindle W to the upper end of 20 it, and is placed between an adjustable collar, G', and the bridge-piece E. According to the position of the collar G', the spring will be more or less compressed, and the pressure caused by the spindle and the pantograph will 25 be counteracted according to its position. I am thus enabled to regulate the pressure exactly according to requirements.

If it be desired to make figures either larger or smaller than the model, I proceed in the 30 following manner—that is to say: After the pantograph has been set for enlarging or reducing in the well-known manner the drills at two of the sides are thrown out of gear, and only that drill which is opposite to the guide-pin is employed, as the side drills in this case would not produce figures corresponding with the model. The operation is effected in the manner above described; but it is not necessary to adhere to a certain definite direction of 35 the guide-pin, which can, if desired, be moved over the model in an irregular manner, while the figure, whether its outline is enlarged or reduced, is always correctly reproduced; but the enlargement or reduction of the outline of 40 the model requires a similar enlargement or reduction with regard to the raised or sunk parts of the picture, which is attained by the following contrivance—that is to say: On the head-piece u, which can be fixed on the central spindle, W, by means of the screws f, the double-armed lever L is pivoted. This lever L can be fixed in a horizontal position by means of the set-screws gg, whereby its up-and-down movement can also be regulated within cer- 45 tain limits. On the said double-armed lever are sliding pieces u and x, which can be shifted easily. The forked piece P is connected with the first sliding piece by a link in which the drill rotates. The sliding piece x is connected 50 by means of the open link x', and other links with the guide-pin P', and indirectly with the pantograph, by means of the connecting-piece

x''. The said guide-pin can easily be moved up or down in the hollow boss, which connects two pantograph-bars with each other. The 70 connecting-piece x'', the lower end of which is connected by a link with the pantograph, can at the other end be moved to and fro in the open link x', and can be fixed thereon by means of a screw, y, on which it is free to oscillate. If, now, for instance, it is desired to reproduce the model in question half-size, then the pantograph is set to the required position, and the lever L is fixed in a horizontal position by the set-screws g g. The said connecting-piece x'' is then fixed in the open link x' by the said screw y, so that it can vibrate on the same as a center, as is shown in Fig. 3. After the drill has been put in rotation by the motive power the guide-pin is moved freely across 80 the model. The pantograph P must now follow the movements of the guide-pin, with which it is connected by means of the slotted link x' and the connecting-piece x'', whether it is moved in a vertical or a horizontal direction. 85 As it has been set to reproduce the model reduced to half-size, the outline of the picture is cut by the drill to the desired reduced scale, and the raised and sunk parts of the model are at the same time correspondingly reduced. 90 The movement of the guide-pin, as above stated, is not transferred direct to the pantograph, but is effected by the slotted link x' and the connecting-piece x''. The relative position of these parts to one another, as 95 shown in the drawings, allows the pantograph to follow the movements of the guide-pin in the desired direction, but reducing it at the same time to one-half, so that when the guide-pin is pushed two centimeters up the pantograph, with the drill, is only raised one centimeter. This operation will be readily understood, and therefore does not require further description. The farther the connecting-piece x''' is fixed to the left on the slotted link x' the 100 more the copy will be reduced.

If it is desired to enlarge the model, then the drill is fitted on the side where the guide-pin was fitted in the above-described operation for reducing the model, and the guide-pin 105 is fixed in the place of the drill.

If it is desired to work from negative to positive, and vice versa—for instance, to convert a negative engraved coat of arms into raised work—then the double-armed lever L is allowed 110 to work freely by slackening the set-screws g g. The central spindle, W, is, moreover, fixed in such a manner that it can rotate, but cannot alter its position vertically. If the guide-pin is brought into a recessed part in the engraving, then a raised part will be produced on the drill side, because the lever L, turning on its pivot f', will be raised as much on the working-side as it is depressed on the other side. In working from positive to negative the reverse takes place.

In order to be able to produce an even smooth surface, another contrivance is applied, by means of which the central spindle, W, with

the pantograph, can always be kept at the same height without preventing it from turning freely. The head-piece U, Figs. 2 and 3, is fixed on the spindle W, by means of a screw, 5 f. On its upper end it has a groove extending around it.

In the bearing on the piece E are the screws e e, Fig. 2, which are screwed so far into the groove in the head U that they do not prevent 10 the latter, and with it the spindle W, from turning freely, but yet prevent them from descending.

As the head-piece u can be fixed in any position on the spindle W, the surface to be operated upon can be of any desired thickness. 15 The drill or tool does not in this case cut from above downward, but from side to side, as in the operation of planing, and the necessary pressure is not obtained by the weight of the 20 spindle, but by the hand directing the guide-pin.

This machine can be used as a substitute for a rose engine-lathe.

Having thus fully described the said invention and the manner of performing the same, I 25 wish it to be understood that I claim—

1. In a model-copying machine, the spindle W, in combination with the pantograph P, the drills and guide-pin b b, the pulleys r, the head-piece u, the collars G G', provided with set-screws, the spiral spring F, the table T, with the raised parts N, having slots in them, the sliding blocks K, the screws D, connected by miter-wheels, and the hand-wheel R, substantially as described, and for the purpose specified. 30

2. The collar or head-piece u, in combination with the set-screws g g, the screw f, the lever L, capable of oscillating on the pivot f', the sliding pieces w and x, the slotted link x', 40 and the connecting-piece x'', substantially as described, and for the purpose specified.

In testimony whereof I have signed my name to this specification in the presence of two subscribing witnesses.

MAXIMILIAN JOSEPH SALM.
